PHOTOGRAPHIC PRINT HOLDER

Lawrence M. Reed, 1435 Sturt Ave., Hewlett, N.Y.

Filed Apr. 28, 1960, Ser. No. 60,354

Term of patent 7 years

(Cl. D61—1)

I claim:

The ornamental design for a photographic print holder, substantially as shown.
